UNITED STATES PATENT OFFICE.

CONRAD DRESSLER, OF CLEVELAND, OHIO, ASSIGNOR TO AMERICAN DRESSLER TUNNEL KILNS, INC., OF NEW YORK, N. Y., A CORPORATION OF NEW YORK.

CONTINUOUS TUNNEL KILN.

Original application filed February 21, 1920, Serial No. 360,505. Divided and this application filed August 31, 1920, Serial No. 407,116. Renewed November 14, 1923.

To all whom it may concern:

Be it known that I, CONRAD DRESSLER, a citizen of the United States, and resident of Cleveland, in the county of Cuyahoga and State of Ohio, have invented certain new and useful Improvements in Continuous Tunnel Kilns, of which the following is a specification.

The general object of the present invention is to provide means for heating, and controlling the temperature in a continuous tunnel kiln.

The various features of novelty which characterize my invention are pointed out with particularity in the claims annexed to and forming a part of this specification. For a better understanding of the invention however, the advantages possessed by it and specific objects attained with its use, reference should be had to the accompanying drawings and descriptive matter in which I have illustrated and described preferred embodiments of my invention.

Of the drawings:

Fig. 1 is a diagrammatic plan with parts broken away and in section of a combination open fire heated kiln and drier; and Figs. 2, 3 and 4 are transverse sections taken on the lines 2-2, 3-3 and 4-4 respectively, of Figure 1.

In the drawings I have illustrated the use of my present invention in an open fire tunnel kiln especially devised for drying and burning brick and comprising a drying chamber B in alignment with, and forming a direct extension of the kiln C proper. The brick carrying cars A enter the drying chamber B at the entrance end B¹ of the drying chamber, and pass first through the drying chamber and then through the kiln chamber proper on track rails D which run from the entrance end B¹ of the drying chamber to the exit end C¹ of the kiln. In passing through the final or cooling zone section of the kiln chamber, the bricks are cooled by atmospheric air drawn in through the end C¹ of the kiln chamber which may be left open or be provided with suitable openings for the admission of this air. The air thus admitted to the cooling zone section of the kiln is withdrawn at intervals along the length of the cooling zone section through ports C⁴ and downcomer passages C³. The portion of the kiln

chamber above the path-way for the goods in the cooling zone section is divided by transverse partitions or barriers C² into a series of compartments open at their lower end. The partitions or barriers C² extend into close proximity with the upper ends of the stacks of brick on the cars A. The downcomer passages C³ are formed in the side walls of the kiln chamber and are connected at their upper ends to the roof compartment between the partitions C² nearest to the furnace zone of the kiln. Each of the other roof compartments is connected by a pair of ports C⁴ to conduits E running along the top of the kiln chamber. The downcomer passages C³ are connected at their lower ends to horizontal tunnels or conduits C⁵ arranged one at each side of the kiln. Blowers F draw air from the conduits E and blow this air through discharge pipes F¹ into the adjacent ends 75 of the conduits C⁵. As shown, each of the blower pipes F¹ terminates in a horizontal nozzle portion F² which discharge an axial jet into the corresponding tunnel C⁵ and thereby exerts the suction effect on the lower end of the corresponding downcomer passages C³ necessary to create the desired flow downward through the passage C³.

At intervals along the length of the high temperature or furnace zone of the kiln, burner chambers G are provided in the side walls of the kiln. These receive air from the passages C⁵, each through a corresponding branch passage G¹. Each chamber G receives fuel gas through a supply connection I, controlled by a valve I¹, from a corresponding gas supply passage I² of which there is one at each side of the kiln. The gas supply passages I² are connected to a gas supply source I³ which may be a gas holder or a gas producer.

Each burner chamber G opens to the interior kiln chamber through a burner nozzle H advantageously formed of carborundum or other highly refractory material and tapered and disposed so that the burning jet delivered by it into the kiln chamber is inclined toward the entrance end B¹ of the drying chamber and is at the level of passages A¹ preferably formed at the tops 100 of the cars A. The passages A¹ are open at their upper sides to the interstices in the stacks of brick mounted on the cars,

Advantageously, the passages A¹, which may be formed in the permanent portions of the car bodies, or in the bottoms of the brick stacks, are arranged herring-bone fashion with each passage inclined to the direction of travel of the cars so as to be parallel to the direction of the jets discharged by the corresponding set of burner nozzles H.

In the normal intended operation of the apparatus disclosed, a portion only of the heated air received by the pipes E through the ports C⁴, is withdrawn from the pipes by the blowers F, and utilized in supporting combustion in the burner chambers G. The remainder of the air entering the pipes E is withdrawn from the latter by blowers J, and is passed from the latter into the drying chamber B through piping J¹. The products of combustion are drawn from the furnace zone of the kiln longitudinally through the kiln chamber by a suitable draft creating device shown as comprising an ex-hauster K with its outlet connected to a discharge stack K¹. Preferably the products of combustion are utilized to impart heat to the drying chamber B without coming into direct contact with the bricks or other goods to be dried, but the manner in which this is accomplished and the specific construction of the drying chamber B and of the portion of the kiln between the drying chamber and the furnace zone of the kiln need not be illustrated and described herein as they form no part of the present invention and are fully disclosed and claimed in my application for patent, Serial No. 360,505, filed February 20, 1920, of which this application is a division.

The carborundum burner nozzles H form effective and durable means for giving the desired velocity and direction to the burning jets entering the kiln chamber through them. The provisions described for withdrawing air from the cooling zone section of the kiln and delivering it to the combustion chambers G insures an adequate supply of highly heated air to the combustion chambers without subjecting the air moving blowers or fans F to the injurious action of the most highly heated air withdrawn from the entrance end of the cooling zone section by the downcomer passages C³.

While in accordance with the provisions of the statutes, I have illustrated and described the best form of my invention now known to me, it will be apparent to those skilled in the art that changes may be made in the form of the apparatus disclosed without departing from the spirit of my inven-

tion as set forth in the appended claims, and that in some cases certain features of my invention may be used to advantage without a corresponding use of other features.

Having now described my invention, what I claim as new and desire to secure by Letters Patent is:—

1. In a continuous tunnel kiln, the combination with a kiln chamber having side walls formed with burner chambers therein, of provisions for supplying air and fuel to said burner chambers, and nozzle members formed of carborundum and connecting said burner chambers to the interior of the kiln chamber.

2. In a continuous tunnel kiln, the combination with a kiln chamber having side walls formed with burner chambers therein, of provision for supplying air and fuel to said burner chambers, and nozzle members formed of carborundum and having tapered nozzle orifices which connect said burner chambers to the interior of the kiln chamber.

3. The combination with a continuous tunnel kiln having fuel burning provision for heating a high temperature portion of the kiln and means for creating a flow of air through a portion of the kiln adjacent its exit end to cool the goods passing through said portion, and means for withdrawing the said air from the kiln and delivering it to said fuel burning portion, said last mentioned means comprising air outlet ports distributed along the length of the kiln, a fan drawing air through some of said outlets adjacent the exit end of the kiln and discharging this air in a jet, and means for utilizing said jet to create a suction drawing air through one of said outlets more remote from the exit end of the kiln.

4. The combination with a continuous tunnel kiln having fuel burning provision for heating a high temperature portion of the kiln and means for creating the flow of air through a second portion of the kiln adjacent its exit end to cool the goods passing through said portion, of means for withdrawing the air from the kiln, comprising a fan drawing air from a part of said second kiln portion more closely adjacent the exit end of the kiln and for discharging this air in a jet, and means for utilizing said jet to create a suction drawing air from a part of said second kiln portion less closely adjacent the exit end of the kiln.

Signed at Cleveland in the county of Cuyahoga and State of Ohio this 23rd day of Aug. A. D. 1920.

CONRAD DRESSLER.
